COMBINATION SAFETY RAZOR AND
SHARPENER

Joseph Pelillo, Ridgefield, Wash.

Application July 14, 1936, Serial No. 90,502

3 Claims. (Cl. 30—35)

My invention relates to safety razors, and its primary purpose is to provide a safety razor frame adapted for using a single safety razor blade over relatively long periods of time by 5 providing means associated with the frame for securely holding the blade in position for conditioning, as by stropping and/or honing.

A further object of my invention consists in so constructing the safety razor frame that it 10 may be encompassed within small space and that it may be used over relatively long periods with practical freedom from mechanical and operating annoyances.

A still further object of my invention consists 15 in providing a support for the razor blade that may be precisely adjusted to meet the operating requirements of the user.

My invention comprises a primary handle member having a sleeve threadably disposed 20 about the central outer surface thereof. A safety shaving head adapted for holding a razor blade in position for shaving is disposed upon one end of the handle member, and a clamping head adapted for holding a razor blade in position for conditioning is disposed upon the opposite 25 site end of the handle member.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

35 In the drawings:

Fig. 1 is a side view of the assembled razor. In this view the clamping head is shown outwardly hinged to facilitate adjusting the clamping means on the safety shaving head.

40 Fig. 2 is a sectional side view of the assembled razor.

Fig. 3 is a top plan view partially in section of the assembled razor.

45 Fig. 4 is a perspective end view of the assembled razor.

Fig. 5 is a perspective end view of the assembled razor illustrating the razor blade held by the clamping head in position for honing and stropping.

50 Fig. 6 is a side view of the razor handle and blade shown in position for conditioning the blade by stropping or honing.

Fig. 7 is a top plan view of the razor blade 55 and a sectional view of the clamping head, taken

on line 7—7 of Fig. 6, looking in the direction indicated.

Fig. 8 is a perspective end side view of the razor blade.

Like reference characters refer to like parts 5 throughout the following views.

My device is comprised primarily of a handle member 1, one end of which is bifurcated at 2, resulting in a top member 3 and a bottom member 4 disposed in parallel. A clamping head 5 is disposed longitudinally of the primary handle member. A guard 6 terminates the head end of the bottom member 4. A toothed comb-like structure 7 terminates the working edge of the guard 6. An outer face 8 of the top member 3 and outer face 9 of the guard 6 lie in a common plane. The clamp 5 is expanded at its outer end and terminates in clamping jaws 10 and 11 that are adapted to encompass the ends of a razor blade 14. Notches 12 and 13 are disposed in the opposite ends of the razor blade 14. These notches are preferably placed near the top edge of the blade and in registry alignment with each other. These notches serve as indexing means for precisely locating the razor blade in place.

Clamp 5 has a stem 15 extending inwardly along the axial center line of the primary handle member. The clamping head is extended to form a fan-like head as illustrated at 16 and an elongated slot 17 is disposed therein, through which adjusting screw 18 passes. The head end of the adjusting screw 18 is a free fit in hole 19 which is disposed within the top member 3. The adjusting screw 18 is threaded into the bottom member 4. The handle member is preferably made of spring material in order that the outer ends of the bifurcated handle member may be moved toward each other against spring tension. Rotation of the adjusting screw causes a relative displacement between the top and lower members of the bifurcated handle member, and consequently causes relative displacement between the cutting edge 22 of the razor blade and the outer ends of the guard teeth 7. Lugs 20 and 21 extend forwardly from the outer ends of the top member 3 and are made to engage with notches 12 and 13 disposed in the ends of the razor blade. The stem 15 is threadably secured to a finger adjusting nut 23 having a sleeve 24 fixed thereto. A relatively long threaded connection is provided between the sleeve 24 and the stem 15 to provide for adequate travel of the clamping head 5 to freely release the razor blade when its removal from 55

the safety shaving head is desired. A stropping clamp 25 is slidably disposed relative to the primary handle member. A reverse bend 26 terminates the outer end of the stropping clamp. 5 A lug 27 is disposed upon the elongated inner end of the stropping clamp. A friction sleeve 28 is disposed about the primary handle member 1, and the stropping clamp extends therethrough. V-shaped notches 29 and 30 are disposed adjacent the back of the razor blade 14. 10 Wedge shaped jaws 31 and 32 are disposed respectively within stropping clamp 25 and on the sleeve 28 and are held in registry alignment with each other, and are adapted for engaging with in the V-shaped notches 29 and 30 of the razor blade, to hold the blade in fixed position for honing and/or stropping.

To place the razor blade within the conditioning head of the razor frame, clamp 25 is moved outwardly to receive the blade between the 20 clamping jaws, in which position the lug 27 engages with a shoulder 33, limiting the outward movement of the clamp 25. A band 34, threadably secured to the primary handle member 1, is made to abut the sleeve 28. When the razor 25 blade has been placed within the clamping jaws 31 and 32 a tight clamping pressure is provided upon the blade by the longitudinal movement of a band 34 against the sleeve 28, said longitudinal movement being effected by the rotation of the 30 threaded band 34 upon the primary handle member 1. This places the razor blade under compression between the jaws of the conditioning head.

While the form of mechanism herein shown 35 and described is admirably adapted to fulfill the objects primarily stated, it is to be understood that it is not intended to confine the invention to the embodiment herein shown and described, as it is susceptible of embodiment in various 40 forms, all coming within the scope of the claims which follow.

What I claim is:

1. In a device of the class described, the combination of a safety razor blade having a substantially thick back, a pair of rectangularly sectioned notches disposed in the ends thereof, a 5 pair of notches having a V-shaped section normal to the blade thickness disposed in the ends thereof between the said rectangularly sectioned notches and the said back, a safety razor frame member having two ends and adapted at one end for holding the safety razor blade in position for shaving and adapted at the other end for holding the safety razor blade in position for conditioning the same.

2. A razor blade, comprised of a one piece member, the said blade being thicker at its back than at any other point, a slot disposed within the oppositely disposed ends of the blade and in registry alignment with each other and that point of the blade ends disposed above the slots being 20 V-shaped and the apex of the V being inwardly disposed from the outer edges of the blade ends.

3. In a device of the class described, the combination of handle member, a stropping clamp disposed longitudinally of the handle member and outwardly extending therefrom, a reverse bend disposed within the outer end of the stropping clamp, V-shaped jaws disposed in the outer end of the handle member and in the outer end of a friction sleeve, and disposed in registry alignment with each other, a lug disposed upon the inner end of the stropping clamp, said lug being adapted for engaging upon a shoulder of the handle member when extended to limit the outward movement of the stropping clamp, a friction 35 sleeve disposed upon the outer end of the handle member, and a band threadably secured to the handle member and adapted for engaging the friction sleeve and for moving the same outwardly longitudinally of the handle member. 40

JOSEPH POLILLO.
